UNITED STATES PATENT OFFICE.

CURTIS HUSSEY VEEDER, OF HARTFORD, CONNECTICUT, ASSIGNOR TO THE VEEDER MANUFACTURING CO., OF HARTFORD, CONNECTICUT, A CORPORATION OF CONNECTICUT.

TACHOMETER.

1,421,865.

Specification of Letters Patent.

Patented July 4, 1922.

Application filed March 23, 1921. Serial No. 454,646.

To all whom it may concern:

Be it known that I, CURTIS HUSSEY VEEDER, a citizen of the United States, residing in the city of Hartford, in the State of Connecticut, have invented certain new and useful Improvements in Tachometers, of which the following is a specification, reference being had to the accompanying drawings, forming a part hereof.

10 This invention relates to instruments of the same general character as that shown in Letters Patent of the United States No. 1,016,906, dated February 6, 1912, and shown and described therein, and in Letters Patent 15 of the United States Nos. 732,975 and 733-358, both dated July 7, 1903, with respect to the speed indicating device, the present instrument, like that shown in Letters Patent No. 1,016,906, including road measuring devices as well as speed indicating devices. In 20 general the speed indicating devices of the present case are substantially like those of the patents above mentioned and the road measuring devices are substantially like 25 those heretofore used, but various improvements in details have been made with a view to the attainment of greater efficiency, accuracy and convenience in the operation and use of the instrument, better structural features, including compactness of the instrument as a whole, and greater facility in manufacture, it being possible in the new instrument to employ for the most part die-castings, without much machining. The 30 invention will be more fully explained herein- 35 after with reference to the accompanying drawings in which it is illustrated and in which—

Figure 1 is a view of the improved instrument in front elevation.

Figure 2 is a view of the same in vertical section on the plane indicated by the broken line 2-2 of Figure 1, looking in the direction of the arrows.

45 Figure 3 is a view partly in horizontal section on the plane indicated by the broken line 3-3 of Figure 1, looking in the direction of the arrows.

50 Figure 4 is a view partly in horizontal section, on the plane indicated by the broken

line 4-4 of Figure 1, looking in the direction of the arrows.

Figure 5 is a detail view of a part to be referred to.

Figure 6 is a detail view of the means for 55 resetting the trip odometer.

Figure 7 is a detail view, in front elevation, of the lower portion of the tachometer with the front plate removed.

Figure 8 is a view in vertical central section, similar to Figure 2 but on a larger scale and with some parts broken out.

Figure 9 is a view in horizontal section on the plane indicated by the broken line 9-9 of Figures 2 and 8.

60 Figures 10, 11, 12 and 13 are detail views of different parts of the paddle-wheel case.

Figure 14 is a detail view showing how the vertical odometer shaft is supported.

Figure 15 is a detail view showing one of 70 the connections from the valve seat to be referred to.

Figure 16 is a detail view of the valve to be referred to.

The working parts of the improved instrument are enclosed within a casing *a*, the front plate *a'* of which has at *a*² a vertical sight opening in front of the tachometer tube, with low speed and high speed scales marked at the right and left thereof, a horizontal sight opening *a*³ in front of the totalizing register or odometer and a sight opening *a*⁴ in front of the trip or resetting odometer. In the rear wall of the casing is an opening for the support *b* for the coupling member *a*⁶ of the flexible drive shaft, such coupling member carrying a bevel gear *b'* by which the tachometer is driven, and a worm *b*² by which the odometer shaft is driven. The bevel gear *b'* meshes with a 75 bevel gear *c* on the upper end of the paddle wheel shaft *c'* and the worm *b*² meshes with a worm gear *d* on the upper end of the odometer shaft *d'*, shown in dotted lines in Figure 1 and in section in Figures 3 and 4. 80 The shaft *d'* is supported in bearings formed in the opposing faces of two frame members as hereinabove described and has secured thereto a worm *d*² and a worm *d*³. The worm *d*² meshes with a worm wheel *e* which, 85

90

95

100

through a reducing transfer device of ordinary description e' , drives the right hand number wheel e^2 of the totalizing odometer e^3 . The worm d^3 meshes with a worm wheel f which drives directly the right hand number wheel of the trip odometer f^2 . The arrangement is preferably such that the number wheel f^3 of the trip odometer is driven at ten times the speed of the right hand number wheel e^2 of the totalizing odometer, so that the right hand number wheel of the trip odometer may register, for example, tenths of a mile. The two odometers or road measuring devices e^3 and f^2 may be of usual construction and are secured to the face plate a' so that they may be read conveniently through the sight openings a^3 and a^4 . The resetting shaft f^3 of the trip odometer f^2 , has secured thereto a spur wheel f^4 engaged by a corresponding pinion f^5 on a shaft f^6 which is mounted in a suitable bearing secured to the face plate a' and, extended through the front plate a' , bears a thumb wheel f^7 so that the observer can conveniently reset the trip odometer when desired.

Within the casing a are supported a main casting g and a supplemental casting h . In the contacting faces of the main casting g and the supplemental casting h , as shown at h' in Figure 6, are formed the bearings for the odometer drive shaft d' , this construction permitting both of these supporting or frame members g and h to be formed as die castings with no boring to receive the shaft d' , which is placed in position as the two frame members are assembled.

The main casting or frame member g is formed with a displacement chamber g' having a base or foot part g^2 , a tubular chamber g^3 , through which passes the paddle wheel shaft e' , a channel g^4 , g^5 from the displacement chamber g' to the top of the casting, a seat g^6 for the bearing of the shaft e' , reservoirs g^7 and g^8 which communicate through upper and lower channels g^9 and g^{10} , indicated in part by dotted lines in Figures 7 and 9, and a spherical valve seat g^{11} . The reservoirs g^7 and g^8 are completed by caps i and i' , which are formed as die castings and are secured in place by screws i^2 . The cap plates i and i' project through the front plate a' , as shown at i^3 in Figures 2, 8 and 9.

At g^{12} on the main casting is formed a seat for a packing k on which rests the lower end of the glass tachometer tube k' , which stands in a niche g^{13} formed therefor in the face of the main casting g and is held in place at its upper end by a packing k^2 and a channeled plate k^3 , the channel k^4 of which establishes communication between the channel g^4 , g^5 of the main casting and the bore of the tube.

A channel g^{14} in the casting g establishes communication between the bore of the tube k' and the spherical valve seat g^{11} , and other

channels g^{15} and g^{16} respectively establish connection between the valve seat g^{11} and the lower or larger paddle wheel chamber and the upper or smaller paddle wheel chamber respectively, as the conditions of operation may require, so that the height at which the indicating liquid stands in the tube k' can be influenced either by the small paddle wheel or the large paddle wheel. 70

The spherical valve l which rests in the valve seat g^{11} , and is suitably channeled at l' , as shown in Figure 16, for co-operation with the channels g^{14} , g^{15} , and g^{16} , is held in its seat by suitable packing l^2 and a nut l^3 and its stem l^4 has secured thereto a pointer or handle l^5 by which the valve can be turned to establish connection between the indicator tube k' and the upper or lower paddle wheel chamber, as may be desired. 80

The displacement plunger m is formed with rack teeth on its side, as shown at m' in Figure 7, and is engaged by a toothed spindle m^2 which passes through the cap plate i^3 and the channel g^9 , being provided exteriorly with a knob m^3 and interiorly with a shoulder m^4 which is held in close contact with the seat formed therefor in the cap plate i^3 , by a spring plunger m^5 . The plunger is guided and held from rotation by a pin m^6 which may be seated in the plate 90 o^2 hereinafter mentioned.

The open lower end of the displacement chamber g' is closed by a plate n which may be held to the base of the casting g' by screws n' , as indicated in dotted lines in Figures 8 and 9, the plate being preferably formed on its upper surface with an annular sealing rib n^2 . In order that the paddle wheel case may be formed by die casting, it is formed in three separate parts o , o' and o^2 , each of which is tapered externally so as to make a tight joint with the tapered interior g^{17} of the base of the main casting, below the displacement chamber. The annular member o is formed on its under side with an 110 annular sealing channel o^3 for the reception of the sealing rib n^2 of the plate n , and is also channeled on its upper side, as at o^4 , to receive the annular member o' , which is channeled radially, as at o^5 , and circumferentially, as at o^6 , to establish communication between the lower paddle wheel chamber and the channel g^{15} . 115

It is chambered on its under side, as at o^7 , to form, with the member o , the larger paddle wheel chamber, and is chambered at its upper side, as at o^8 , to receive the upper member o^2 . The latter is chambered on its under side, as at o^9 , to form, with the member o' , the upper paddle wheel chamber, and is channeled radially as at o^{10} 120 and circumferentially as at o^{11} , on its under side, to establish communication between the upper paddle wheel chamber and the channel g^{16} above referred to. On its upper side the member o^2 is formed with a sleeve o^{12} , 125

130

provided with openings o^{13} and o^{14} , the sleeve permitting the passage of the paddle wheel shaft c' , and the movement of the liquid in the displacement chamber under the influence of the displacement plunger n . It will be evident that by the formation of the paddle wheel casing as three separate members, as described, each member can be made as a die casting, with the respective channels formed as described in the die casting, without subsequent boring or machining of any kind and that when these several members are properly superimposed and pressed into the tapered foot of the main frame or casting, below the displacement chamber and are secured in place by the cap plate, all joints will be tight.

I claim as my invention:

1. In an instrument of the character described, the combination of a main frame having an open base, two separate members fitted within the base and chambered to form a paddle wheel chamber, one of said members having formed in its face adjacent the other member a radial channel and a circumferential channel, and means to retain the said members in place.

2. In an instrument of the character described, the combination of a main frame having an open base tapered interiorly, two separate members tapered exteriorly to fit within the base and chambered to form a paddle wheel chamber, one of said members having formed in its face adjacent to the other member a radial channel and a circumferential channel, and means to retain said members in place.

3. In an instrument of the character described, the combination of a main frame having an open base, two separate members fitted within the base and chambered to form the paddle wheel chamber, one of said members having formed in its face adjacent the other member a radial channel and a circumferential channel, and a cap plate secured to the main frame to close the opening in the base and retain said members in place.

4. In an instrument of the character described, the combination of a main frame having an open base, three separate members fitted within the base and chambered to form a small paddle wheel chamber and a large paddle wheel chamber, each of two of said members having formed in its face adjacent to the next member a radial channel and a circumferential channel, and means to retain said members in place.

5. In an instrument of the character described, the combination of a main frame having an open base, an indicator tube, two separate members fitted within the base and chambered to form a paddle wheel chamber, one of said members having formed in its face adjacent to the other member a radial channel and a circumferential channel, a

channel being formed in said main frame to establish communication between the indicator tube and said circumferential channel and means to retain said members in place.

6. In an instrument of the character described, the combination of a main frame having an open base, three separate members fitted within the base and chambered to form a small paddle wheel chamber and a large paddle wheel chamber, each of two of said members having formed in its face adjacent to the other member a radial channel and a circumferential channel, an indicator tube, channels being formed in the main frame to establish communication between the indicator tube and the said circumferential channels respectively, a valve to determine the connection between the indicator tube and the one or the other of said circumferential channels and means to retain said members in place.

7. In an instrument of the character described, the combination of a main frame, means forming in the base of the main frame a small paddle wheel chamber and a large paddle wheel chamber, an indicator tube, the main frame having channels to establish communication between the indicator tube and the small and large paddle wheel chambers respectively, said channels being formed for communication with a valve seat, and a valve seated in said valve seat for determining the connection between the indicator tube and the small and large paddle wheel chambers respectively.

8. In an instrument of the character described, the combination of a main frame having formed in its base a displacement chamber with an open lower end, a separate member fitted in the open lower end of the main frame to form below the same a paddle wheel chamber and having an upwardly extended sleeve open at its lower end for communication with the displacement chamber, a displacement plunger mounted on said sleeve, means to complete the paddle wheel chamber, and an indicator tube, channels being formed in the main frame for communication between the displacement chamber and the upper end of the indicator tube and between the lower end of the indicator tube and the paddle wheel chamber.

9. In an instrument of the character described, the combination of a main frame having a paddle wheel chamber, a displacement chamber and a reservoir chamber formed partly therein, the main frame having also upper and lower communicating channels between the reservoir chamber and the displacement chamber, and a cap secured to the main frame opposite said channels to close the reservoir chamber.

10. In an instrument of the character described, the combination of a main frame having a paddle wheel chamber and a seat

70

for an indicator tube, said main frame having also a channel of communication between the lower end of the indicator tube and the paddle wheel chamber and a channel of communication between the paddle wheel chamber and the upper end of the frame, and a channeled cap secured to the upper

end of the frame, its channel establishing communication between the upper end of the indicator tube and the upper end of the last named channel of the frame.

This specification signed this 14 day of March A. D. 1921.

CURTIS HUSSEY VEEDER.
